UNITED STATES PATENT OFFICE.

ALBERT HUPP, OF WASHINGTON, DISTRICT OF COLUMBIA.

RAILWAY MAIL-EXCHANGE APPARATUS.

1,203,623.

Specification of Letters Patent.

Patented Nov. 7, 1916.

Application filed February 25, 1915. Serial No. 10,532.

To all whom it may concern:

Be it known that I, ALBERT HUPP, a citizen of the United States, and resident of Washington, District of Columbia, have invented certain new and useful Improvements in Railway Mail-Exchange Apparatus, of which the following is a specification.

This invention relates to mail exchange apparatus and more particularly to automatically operating mechanism carried by a mail car and adapted to receive mail bags from a station crane located along the railroad.

The object of the invention is to provide a comparatively simple and efficient mechanism for this purpose which shall be adapted to receive the mail bags, when the train is moving at high speed, without injuring any of the contents of the bags.

With the foregoing and other objects in view, as will appear from the following description, the invention may be embodied in different forms one of which is illustrated in the accompanying drawings.

In the drawings—Figure 1 is a side elevation of a part of a mail car showing my improved receiving mechanism applied thereto; Fig. 2 is a transverse section of a mail car, in the rear of the receiving mechanism and looking forward; Fig. 3 is a horizontal section through the side of the car; the receiving chute being shown in plan.

Referring to the drawings; 10 indicates the side of a mail car which is provided with a doorway 11, the doorway being closed by a sliding door 12. A vertical tubular shaft 13 is supported in a step bearing 14 and by a bracket 15 and has secured thereto a shaft 16 which projects through the floor of the car and has attached thereto an operating arm 17. The shaft 16 is also supported in a bearing 18. The brackets 19 are secured on the shaft 13 and have secured thereto the substantially horizontal bars 20, these bars being preferably tubular so as to lessen the weight. The bars 20 project through the doorway 11 and have secured to the inner sides thereof a plate 21, this plate extending to the outer ends of the bars 20 and forming a rigid connecting means between the ends. The bars 20 with the plate 21 constitute a receiving chute for the mail bags and the inner ends of the bars, within the car, are bent downwardly as indicated at 22. In order to widen the chute, where it passes through the doorway, the upper bar 20 is bent upwardly

as indicated at 23 and the lower bar is bent downwardly as indicated at 24. An additional bar 25 is secured to one of the brackets 19 and to the upper bar 20 by means of a plate 26. Short bars 27 and 28 are provided above the lower bar as shown in Fig. 1 and are secured to the lower bar by means of a plate 29.

Referring to Fig. 3 it will be seen that the receiving chute has its outer end arranged against the side of the car when in the inoperative position. The chute is protected, in the inoperative position, by means of an angle iron 30 which is secured to the side of the car in front of the forward end of the chute and along the upper edge thereof, as clearly shown in Fig. 1. The bearing bracket 15 is secured to a bracket 31, which is bolted to the side of the car and, in order to give additional support to the upper end of the shaft 13, a crossbar 32 is arranged on the interior of the car and provided with an elbow 33 on an extension 34 on which the shaft 13 is adapted to turn. The bar 32 extends across the car and has a similar connection with a vertical shaft 13'. The shaft 13' is in all respects, preferably similar to the shaft 13 and carries a receiving chute which projects through a doorway arranged opposite to the doorway 11 so that the car will be adapted to receive mail from either side of the track. Since the receiving chute indicated at the left hand side of Fig. 2 is in all respects similar to the chute at the right hand side of this figure, it is believed that a detail description thereof is not necessary.

By turning the shaft 13 the receiving chute may be moved to the dotted line position indicated in Fig. 3, in which position it is adapted to receive mail from the station cranes, (not shown).

In order to firmly support and brace the receiving chute in the extended position there is secured to the outer side of the chute a member 35 to which the links 36 are pivotally connected. These links are secured together by a cross-member 37 and have their rearward ends pivoted to a vertical rod 38 which is slidable in the slots 39 in the guide members 40 which are secured to the side of the car. When the chute is in the extended position the links 36 engage the rearward walls 40' of the guide members 40 and thus enable the links 36 to brace the chute.

Any suitable actuating mechanism may be

employed for rocking the shaft 13 and an example of such mechanism is shown and described in my earlier application Serial No. 771,041, filed May 31, 1913.

5 On account of the bars 20 being spaced apart and, as shown in Fig. 3, passing through the doorway 11 at a point remote from either side of the doorway, it is necessary to provide means for closing the spaces 10 between the bars 20, when the door 12 is in the closed position, otherwise, there would be objectionable openings permitting the entrance of air and dust between the bars. For the purpose of closing these spaces the 15 door 12 is slotted as indicated at 41 to permit it to be moved to the closed position, in which it engages the abutment 42. The series of slots 41 leave tongues 42' which enter the spaces between the bars 20 and co- 20 operate with the parts 43 of the brackets 19 to close the spaces between the brackets. In order to provide a substantial construction and support the tongues 42' plates 44 and 45 are arranged on the opposite sides of 25 the door and secured to the tongues as shown in Figs. 1 and 3.

Any suitable mechanism may be employed for opening the door and an example of such mechanism is shown in my earlier application above referred to.

In the operation of the receiving chute it is moved to the extended position shown in Fig. 3 and in this position, is adapted to engage a mail bag and remove it from the 35 supporting crane and, as the car moves forward, the bag slides along the inner side of the chute and through the doorway 11 into the car. The friction between the chute and the bag serves to retard the motion of the 40 latter and the downward bends 22 at the inner ends of the bars 20 deflect the bag to the floor of the car and serve to increase the friction between the bars and the bag. By having the bars 20 extend through the doorway 45 and into the car, without break, there is provided a continuous path or chute for the bags which will insure a thoroughly safe delivery of the bags into the car.

Having thus described my invention what 50 I claim is—

1. In apparatus of the class described,

Copies of this patent may be obtained for five cents each, by addressing the "Commissioner of Patents, Washington, D. C."

the combination with a railway car having a side doorway, of a vertical shaft rotatably supported on the interior of the car, brackets secured on said shaft, substantially horizontally arranged spaced bars secured to said brackets and normally projecting through said doorway, means securing the outer ends of said bars together so as to form a mail-receiving chute, and a sliding door, for said doorway, having slots to receive said bars.

2. In apparatus of the class described, the combination with a railway car having a side doorway, of a vertical shaft rotatably supported on the interior of the car, brackets secured on said shaft, substantially horizontally arranged spaced bars secured to said brackets and projecting through said doorway, means securing the outer ends of said bars together so as to form a mail-receiving chute, and a sliding door, for said doorway, having horizontally projecting tongues adapted to enter the spaces between said bars and coöperate with said brackets 75 to close the opening between the rear of said bars and the side of said doorway.

3. In apparatus of the class described, the combination with a car having a side doorway, of a vertical shaft rotatably supported 80 on the interior of the car, a plurality of substantially horizontal bars secured to said shaft and normally projecting through said doorway, said bars having their outer ends secured together to form a mail-receiving 85 chute and their inner ends bent downward.

4. In apparatus of the class described, the combination with a car having a side doorway, of a vertical shaft rotatably supported on the interior of the car, a mail 90 receiving chute secured on said shaft and projecting through said doorway, and a bracing member pivoted to said chute and having a sliding connection with the side of the car.

In testimony whereof I affix my signature in presence of two witnesses.

ALBERT HUPP.
